UNITED STATES PATENT OFFICE.

JOSEPH KENNEDY, OF NEW YORK, N. Y., ASSIGNOR TO THE CLEMENTS COMPANY, OF NEW YORK, N. Y., A CORPORATION OF NEW YORK.

WALL-SOCKET.

1,234,177.

Specification of Letters Patent.

Patented July 24, 1917.

Original application filed August 14, 1913, Serial No. 784,672. Divided and this application filed June 19, 1914. Serial No. 846,092.

To all whom it may concern:

Be it known that I, JOSEPH KENNEDY, a citizen of the United States of America, and a resident of New York, county and 5 State of New York, have invented certain new and useful Improvements in Wall-Sockets, of which the following is a specification, reference being had to the accompanying drawings, forming a part thereof.

10 My invention relates to wall sockets or plugs, such as are inserted in walls, floors, or other structures of material which will not readily receive and hold the threads of a bolt for the purpose of forming anchor- 15 age members for bolts and the like, and its object is to provide a simple device which will be securely held in a hole into which it is driven.

This and other objects and advantages 20 of my invention will appear in the following specification in which the invention may be described, and its novel features will be set forth in appended claims.

Referring to the drawings:

25 Figure 1 is a longitudinal sectional view of a structure embodying my invention, which structure is shown in transverse sectional views in Figs. 2, 3 and 4, the sections of these figures being taken respectively on 30 the lines 2—2, 3—3 and 4—4 of Fig. 1.

Another socket embodying my invention in a modified form is shown in longitudinal sectional elevation in Fig. 5, and in transverse sections in Figs. 6, 7, and 8, the sections of these figures being taken respectively on 35 the lines 6—6, 7—7 and 8—8 of Fig. 5.

A still further modification of this idea is illustrated in longitudinal section in Fig. 40 9, and in transverse sections in Figs. 10, 11 and 12, the sections in these figures being taken respectively on the line 10—10, 11—11, and 12—12 on Fig. 9.

Fig. 1 shows a shell 10 of soft metal, 45 which is made up of portions of different forms and sizes. The first portion of this shell is conical outside and cylindrical inside.

Fig. 2 is a section of this part of the 50 shell.

The central portion of this shell which is shown in transverse section in Fig. 3 is circular outside and elliptical inside.

The other part of this shell which is

shown in transverse section in Fig. 4 is 55 polygonal both inside and outside.

Fig. 5 shows a shell 10^a also of soft metal, the outside of which is formed of cylinders of different sizes. The bore of this shell is tapered and as shown, is circular in cross- 60 section.

The structure of Figs. 9—12 is an integral shell 10^b, the first portion of which is illustrated in transverse section in Fig. 10 and is elliptical on the outside with a cylindrical 65 threaded bore, the threads being designated by the reference numeral 11. The next portion of this shell of which Fig. 11 is a cross-section is polygonal outside and its bore is in the shape of a polygon formed by internally projecting lugs 12. The other portion of the shell which is shown in cross-section in Fig. 12 is elliptical on the outside and its bore, which is formed of longitudinally 70 tapered ribs 13, is also elliptical. 75

The sockets are of soft metal such, for example, as lead. A part of the exterior may be polygonal so that the corners oppose any turning tendency which may be caused by the insertion of a bolt and the outer end 80 may be conical so that the mouth of the orifice will be completely filled. Between these two parts is an intermediate section which should not be crushed when the sockets are 85 driven in.

The screw threads of the bolts engage and cut their own threads in the sockets when they are inserted. The first section of the sockets may be of smooth bore to receive the unthreaded part of the shank of a standard lag bolt. The intermediate section may be of an internal cross-section of elliptical shape so that the screw threads will be cut into the parts thereof of smaller diameter and the parts thereof of larger diameter 90 will then form a clearance for the displaced metal. The inner section may then be of polygonal cross-section so as to get a greater number of surfaces into which the threads are cut. 95

I have shown several modifications of structure to show that the invention is not limited to any specific form of construction and that I intend no limitations other than those imposed by the appended claims. 100

This application is a division of an application filed by me on the 14th day of August, 1913, and given Serial No. 784,672, 105

and which I have assigned to The Clements Company, a corporation of the State of New York.

What I claim is:

- 5 1. A wall socket comprising a circumferentially continuous hollow shell of soft metal open from end to end having an intermediate portion of one external form in cross-section, and end portions of other 10 external forms in cross-section, said intermediate portion having an internal form in cross-section unlike the internal form in cross-section of either of the end portions.
- 15 2. A wall socket comprising an integral circumferentially continuous hollow shell of soft metal open from end to end having a

central portion of one form and size and external cross-section, and end portions of other forms and sizes in cross-section, said central portion having a bore of one form in 20 cross section and said end portions having a bore coaxial with the central portion but unlike the central portion in cross-sectional form, the outer end portion being of frustoconical shape.

25

In witness whereof, I have hereunto set my hand in the presence of two subscribing witnesses, this 11th day of June, 1914.

JOSEPH KENNEDY.

Witnesses:

I. B. MOORE,
I. MULCAY.
